UNITED STATES PATENT OFFICE.

WILLIAM E. SHERWOOD, OF CANASTOTA, NEW YORK.

ROTARY CONVEYER DUMP BOX.

Application filed December 21, 1926. Serial No. 156,131.

This invention relates to coal trucks and analogous vehicles for carrying coal, broken stone, grain and other more or less comminuted materials and refers more particularly to the construction of the box and to the means for unloading the materials therefrom.

In delivering materials of this character it is found that the inlets for the repositories for the materials are arranged at widely varying levels relatively to the position of the vehicle and also at greater or less distances from said vehicle so that in some instances the materials may be discharged by gravity from the box while in other cases it must be elevated above the normal level of the box and in order to meet these conditions various devices have heretofore been proposed for raising and lowering the box to permit the gravity discharge of the materials into the inlet of the repository.

This elevation of the entire box with the load therein involves the use of expensive machinery and considerable power for its operation in addition to the loss of time required in the necessarily slow raising and lowering of the box.

The main object of the present invention is to construct the vehicle box in such manner that the materials therein will automatically gravitate toward the center thereof and to install in the center of the box a rotary conveyer of simple construction operable preferably by the motor of the vehicle for automatically receiving and conveying the materials from the bottom of the box upwardly some distance above the top thereof for automatic discharge into one or the other of a pair of laterally extending chutes leading from the top of the conveyer so that the materials may be elevated and discharged by gravity at either side of the vehicle directly into the inlet of the repository or into other chutes leading therefrom to said inlets.

Another object is to provide means whereby the unloading device may discharge the material at lower levels at either side thereof.

A further object is to provide means operable at will for controlling the flow of the material from the interior of the box to the conveyer.

Other objects and uses relating to specific

parts of the machine will be brought out in the following description.

In the drawings:—

Figure 1 is a top plan of my improved dump box and conveyer therein.

Figures 2 and 3 are enlarged transverse vertical sectional views taken in the planes of lines 2—2 and 3—3 respectively, Figure 1.

Figure 4 is an enlarged top plan of the conveyer and adjacent separate portion of the box, partly broken away and showing the housing for the conveyer in section.

Figure 5 is an enlarged longitudinal vertical sectional views taken in the plane of line 5—5, Figure 1.

Figure 6 is an enlarged detail sectional view taken in the plane of line 6—6, Figure 3.

The vehicle box or body —1— in which the material is conveyed from place to place is mounted upon a chassis frame —2— composed of lengthwise sills —3—, cross bars —4— and braces —5—, said box being rectangular in top plan but hopper-shaped so that its bottom walls —6— and —7— incline downwardly from the ends and sides to the center except that a relatively small portion as —8— at the longitudinal and transverse center of the bottom is substantially flat and horizontal and rests directly upon the intermediate cross bars —4— while the inclined bottom portions are supported directly upon the braces —5— which, in turn, are secured to the opposite end cross bars —4— as shown in Figure 5.

The interior of the box —1— is divided by longitudinally spaced transversely extending partitions —9— into opposite end compartments —10— and an intermediate compartment —11—, said partitions extending upwardly from the opposite ends of the horizontal bottom portion —8— to the top of the box and from side to side thereof in parallel relation to form a housing for the rotary conveyer presently described and thereby to prevent the passage of the materials from the compartments —10— to the intermediate compartment —11— except as controlled in a manner by suitable gates as hereinafter explained.

An additional transverse partition —12—

extends from one of the inclined bottom walls —6— upwardly some distance above the top of the box and from side to side thereof in parallel spaced relation to one of the partitions —9— to form an additional compartment —13— for receiving a portion of the operating means for the rotary conveyer, the opposite sides of said compartment —13— being closed by upright partitions —14— extending upwardly from the inclined bottom walls —7— above the top of the box —1— as shown in Figure 2 to prevent the passage of the materials from the compartments —10— to the compartments —13—.

The partitions —9— are provided with relatively small openings —15— extending upwardly from the bottom wall —8— to permit the passage of the materials from the lower portions of the compartments —10— to the lower portion of the compartment —11— and are controlled by vertically slideable gates —16—, Figures 2 and 5.

These gates —16— are guided in upright ways —17—, Figure 3, and each gate is adapted to be opened and closed from either side of the machine by a pair of bell crank levers —18— which are pivoted at —18'— to the adjacent partition —9— at opposite sides of the transverse center thereof.

The lower arms of each pair of bell crank levers —18— are connected by a link —20— to the adjacent gate —16— while their upper ends are connected to suitable operating members —21— which extend laterally in opposite directions from the upper ends of their respective levers —18— toward and above the opposite side walls of the box where they are conveniently accessible for operation.

The gates —16— and their operating levers —18— together with the links —20— are preferably located within the compartment —11— where they are protected by the partitions —9— against contact with the main body of the material in the box except as portions of the gates —16— are exposed to such contact through the relatively small openings —15—.

The lower portions of the compartment —13— is also divided by transverse partitions —21— extending upwardly from the bottom walls —7— at opposite sides of and above the adjacent opening —16— and in equally spaced relation to the adjacent portions of the transverse partitions —14— so as to form passages —22— for the operating belt of the rotary conveyer mechanism, said partitions —21— also serving to prevent contact of the materials passing through the opening —16— with said belt.

The bell crank levers —18— of each pair are preferably connected by separate links —20— to their corresponding gate —16— to compensate for the different arcs of move-

ment of the adjacent ends of the levers when operated to open and close the gate.

Rotary conveyer mechanism.

A rotary horizontal shaft —23— is journaled in suitable bearings —24— on the upper portions of the partitions —9— near, but just below the top of the box —1— and midway between the opposite sides of the box so as to extend along the longitudinal center thereof wholly between the left hand end wall —9— of the compartment —13—, Figure 5, and the outer end wall —12— of the compartment —13— so as to protect the bearings —24— from contact with the material in the box —1—.

A hub —25— is keyed or otherwise secured to the intermediate portion of the shaft —23— within the compartment —13— and carries at its left hand end, Figure 5, a series of, in this instance six, radially extending blades —26— arranged in uniformly spaced relation circumferentially and having their inner ends riveted or otherwise secured to the hub —25— and their intermediate portions connected to the other end of the hub by braces —27— for holding them in fixed relation to the hub.

These blades are substantially flat and of uniform area and are preferably tapered inwardly from their outer ends which are relatively wide as compared with their inner ends for a purpose presently described, said blades being preferably made of sheet metal and adapted to travel in the same vertical plane of the box —1—.

The radial length of the blades is also uniform and sufficient to extend into relatively close proximity into the opposite side walls of the box and also a considerable distance above the top of the box and are utilized as a part of the means for conveying the material from the bottom of the compartment —13— upwardly above the top of said box as the shaft —23— is rotated.

A sprocket wheel —28—, Figures 2 and 5, is secured to the shaft —23— within the compartment between the partition —12— and adjacent partition —9— and is connected by a link belt —29— to relatively smaller pinions —30—, —31— and —32— which are secured to separate shafts —30'—, —31'— and —32'—, the latter being journaled in suitable bearings on the underside of the adjacent cross bar —4— to extend lengthwise of the box —1— in a plane below the bottom thereof.

One of the shafts as —31'— may be rotated by any suitable means preferably through connections with the vehicle motor not shown, nor necessary to herein illustrate or describe since the means for operating the shaft forms no part of my present invention.

It is now evident that the rotation of the

shaft as —31— will transmit rotary motion to the conveyer shaft —23— through the medium of the link belt —29— and sprocket wheel —28—, thereby rotating the blades —26—.

A circular ring —33— is riveted or otherwise secured to the outer faces of the blades —26— concentric with the axis of the shaft —23— some distance inwardly from the outer ends of the blades and serves to hold said blades rigidly in circumferentially spaced relation and also to receive and support a plurality of axially extending tie rods or spacing bolts —34— which are bolted or otherwise secured at one end to said ring to extend lengthwise into the compartment —13— between the blades —26— for receiving and supporting at their opposite ends a similar circular ring —35— and 20 for holding said rings in axially spaced parallel relation wholly within the compartment —13—.

An additional set of, in this instance six, relatively short blades —36— are riveted or otherwise secured at their inner ends to the ring —35— in opposed relation to the outer ends of the blades —26— with which they correspond as to circumferential width and radial projection beyond their respective rings thereby forming intervening spaces for the reception of the material between them when the gates —15— are open and the conveyer is being rotated.

The rings —33— and —35— are each provided with a series of relatively short axially projecting bolt studs —37— forming bearings for a corresponding number of rollers —38— projecting toward each other from their respective rings and arranged in uniformly spaced relation circumferentially between the blades —26— and —36— for receiving and supporting additional adjacent circular rings —39— concentric with and of slightly greater diameter than the rings —33— and —35—.

These rings —39— are arranged in axially spaced relation just inside of the adjacent blades —26— and —36— with sufficient clearance to permit their free circumferential movement relatively thereto and serve to receive and support between them a series of sweep paddles or plates —40— corresponding in number to the number of blades —26— and arranged in radial planes 55 in uniformly spaced relation circumferentially so as to extend across the space between the blades —26— and —36— at substantially right angles thereto for engaging and conveying the material from the bottom of the compartment —11— some distance above the top of the box —1—.

Suitable diagonal braces —41—, Figure 3, are riveted or otherwise secured at their outer ends to opposite faces of the plates —40— and have their inner ends riveted or

otherwise secured to the inner faces of the adjacent rings —39— to assist in holding the plates in rigid relation to the ring, the inner opposite edges of the plates being additionally held against circumferential movement 70 on the ring by brackets —42—, Figure 3.

The bearings —24— for the conveyer shaft —23— are mounted upon angle bars —43— which are secured by spot welding or any other suitable fastening means to the inner faces of the partitions —9—, Figures 3 and 5, and upon these transverse bars are mounted a pair of lengthwise bars —44— arranged at equal distances from and at opposite sides of the shaft —23— just at the 80 outside of the path of rotation of the outer ends of the blades —26— and —36—.

A relatively large circular drum —45— of sheet metal or other suitable material is riveted or otherwise secured to the inner faces of the lengthwise bars —44— concentric with the axis of the shaft —23— with its lower side or bottom portion —8— resting upon the upper faces of the cross bars —2—.

This drum —45— extends entirely around the outer ends of the blades —26— and —36— and paddle plates —40— with just sufficient clearance to prevent frictional contact therewith, said drum being also extended axially some distance beyond the blades —26— and —36— and, therefore, beyond the opposite ends of the paddle plates —40— to hold the material against axial displacement while being carried upwardly from the bottom —9— to the top of the conveyer by the plates —40— and between the blades —26— and —36—.

An inner relatively smaller stationary circular drum —46— of sheet metal or equivalent material is riveted or otherwise secured to another pair of lengthwise bars —47— on the cross bars —43— to hold said drum in concentric relation to the shaft —23—, said inner drum being additionally supported by braces —48— which are connected to a hub —49— on the shaft —23— at the inner end of the hub —25— as shown in Figure 5, the hub —49— being loose on the shaft to permit the latter to turn freely therein and through the medium of the braces —48— serving to hold the inner drum —46— concentric with the shaft.

This drum —46— extends endwise across the inner edges of the conveyer plates —40— and also across the inner faces of the bars —34— between but in close proximity to the inner faces of the blades —26— and —36— with just sufficient clearance to avoid friction with those parts.

The object of this inner drum —46— is to prevent inwardly displacement of the material as it is carried upwardly from the bottom —8— around the periphery of the drum by the conveyer plates —40—.

A portion of the peripheral length of the inner drum —46— at the top thereof is cut away to form an opening —50— through which the material which is carried upwardly around the periphery of the drum by the conveyer plates —40— is discharged on to an underlying axially inclined extension chute —51— of a main chute —52— which is centrally supported upon and secured to the upper edge of the partition —12—, Figure 5, the extension —51— being additionally supported by a brace —53— on the hub —49—.

The main chute —52— is located at one end of the conveyer housing and is provided with opposite laterally and downwardly extending inclined branches —54— resting upon the upper edges of opposite sides of the box —1— as shown in Figure 2 for discharging the material by gravity to either side of the box.

For this latter purpose the conveyer including the blades —26— and —36— and plates —40— is rotatable in reverse directions by any suitable mechanism connected to the shaft —31—, not necessary to herein illustrate or describe.

This reverse motion, however, of the conveyer, taken in connection with the resistance of the material contacting with the plates —40—, is utilized to automatically shift the ring —39— and plates —40— carried thereby from normal registration with one edge of the blades —26— and —36— to the opposite edges of the same blades and to stop the angular movement of the ring —39— when the plates —40— are registered with one or the other edges of the blades —26— and —36— so as to form pockets between the blades with the plates —45— at the backs of the pockets.

For this purpose the bolts —34— connecting the opposite rings —33— and —35— are arranged in pairs, those of each pair being located at opposite edges of each set of blades —26— and —36— while the ring —39— is provided with a plurality of pairs of circumferentially spaced stops —55—, those of each pair being arranged at opposite sides of the adjacent conveyer plates —40— to project inwardly between the corresponding pairs of bolts —34— whereby as the conveyer is rotated in either direction the engagement of any one of the conveyer plates —40— with the fuel will cause the ring —39— with the conveyer plates —40— thereon to shift circumferentially in the opposite direction until limited by the engagement of the nearest stops —55— with the adjacent bolts —34—.

This limitation of the circumferential movement of the conveyer plates —40— will cause the latter to convey the material in the direction of rotation of said conveyer from the bottom —8— of the compartment

—11— upwardly between the outer and inner drums —45— and —46— until said material is discharged through the opening —50— on to the extension chute —51— from which it passes by gravity in to the main chute —52—.

Suitable means is provided for deflecting the material delivered from the extension —51— on the extension —52— to either of the branch chutes —54— and for this purpose is provided a deflecting plate —56—, Figure 2, which is adapted to be attached to and removed from either one of a pair of hooks —57— on opposite sides of the extension —51—, Figures 2 and 5.

For example, if the material is to be delivered into the left hand branch chute —54—, Figure 2, the deflector plate —56— will be attached to the right hand hook —57— with its free end resting upon the upper portion of the bottom of the left hand chute.

On the other hand, if the material is to be discharged into the right hand branch —54—, the deflector plate will be detached by hand from the left hand hook —57— and attached to the right hand hook with its free end resting upon the upper portion of the bottom of the branch or a reverse portion from that shown in Figure 2.

It is sometimes desirable or necessary to discharge the material at a lower level and close to one side or the other of the vehicle and for this purpose the lower portions of opposite sides of the outer drum —45— are provided with openings —58— and suitable closures —59— hinged to swing outwardly and downwardly from their closed position so as to rest in downwardly and outwardly inclined planes when open to form guides along which the material may be discharged into an additional chute —60— shown by dotted lines in Figure 3, said doors being held in their closed positions by locking members —61—, Figure 3.

Operation.

Assuming that the box —1— is filled with coal or other material capable of gravitating along its inclined bottom toward the openings —15— in the end walls of the compartment —11— and that the shaft —23— carrying the rings —33— and —35— and conveyer blades —26— and —36— and plates —40— are being rotated.

Then, by opening one or the other or both of the gates —16— will allow the material to pass through the opening or openings —15— into the compartment —11— where it will be carried upwardly between the blades —26— and —36— by the conveyer plates —40— due to the engagement of the bolts —34— with the adjacent stops —55—.

If it is desired to discharge the material in the lower level the corresponding door

—59— will be opened to permit the discharge of the material through the opening —58—.

On the other hand, if it is desired to discharge the material at a higher level both of the doors —59— will be opened and locked whereupon the material will be carried upwardly to the top of the inner drum —46— where it will be discharged through the opening —50— into the chute —51— and thence from said chute into the main chute —52— and through one or the other of its branches —54— according to the adjustment of the deflecting plate —56—.

If the direction of rotation of the conveyer is reversed the ring —39— and plates —40— carried thereby will be shifted circumferentially until limited by the engagement of stops —55— with the opposite posts —34— at which time the plates —40— will be registered at opposite edges of the blades —26— and —36— ready for a repetition of the operation previously described.

What I claim is:—

- 25 1. A device for unloading materials from containers comprising inner and outer circular drums arranged in concentric radially spaced relation about a horizontal axis, means for feeding the material to be conveyed into said space below the axis, a conveyer having carriers movable circumferentially of and within said space for feeding the material therethrough from the bottom to the top of the inner drum, and means for rotating the conveyer.
- 30 2. A device for unloading materials from containers comprising a circular drum concentric with a horizontal axis and provided with an opening in its upper side, a conveyer having carriers movable circumferentially around and in close proximity to the periphery of the drum, means for feeding the material to be conveyed into the path of movement of the carriers below the axis of the drum, and means for rotating the conveyer for carrying the material circumferentially around the drum from the underside to the opening in the top thereof.
- 35 3. An unloading device of the character described as in claim 2 in which the conveyer is surrounded by a circular drum concentric with the first-named drum and provided with an opening below said axis and a closure movable to and from a position
- 40 across the opening.

4. An unloading device of the character described as in claim 2 in which an axially-extending chute projects into one end of the drum beneath the opening in the top thereof for receiving the material discharged into said opening by the conveyer.

5. An unloading device of the character described as in claim 1 in which the inner drum is provided with an opening in its top for receiving the material conveyed thereto by the conveyer, the outer drum being provided with openings in opposite sides thereof and in a plane below the opening in the top of the inner drum and closures for the openings in the outer drum hinged to swing outwardly and downwardly from their closed positions to allow the discharge of the material through either of the last-named openings.

6. An unloading device of the character described, comprising a rotary support revolvable about a horizontal axis, blades secured to the support in opposed axially spaced relation to rotate therewith, an additional support adjustable about said axis and provided with paddle plates movable between opposed blades of the first-named support, means for feeding material to be conveyed between the opposed blades below said axis as the conveyer is rotated to be conveyed by the paddle plates upwardly and circumferentially thereby, the second-named support being adapted to be moved circumferentially a limited distance by contact of the paddle plates with the material, means for limiting the angular movement of the second-named support to register the paddle plates with different portions of the blades of the first-named support as the conveyer is rotated in reverse directions, and means for rotating the conveyer.

7. An unloading device of the character described as in claim 2 in which a chute extends into one end of the drum beneath the opening in the top thereof and is provided with opposite downwardly inclined branches, and a deflector plate movable to reversely inclined positions adjacent the junction of the opposite branches of the chute for deflecting the material into each branch.

In witness whereof I have hereunto set my hand this 14th day of December, 1926.

WILLIAM E. SHERWOOD.
